UNITED STATES PATENT OFFICE.

JOHN C. HENDERSON, OF WASHINGTON, DISTRICT OF COLUMBIA.

COMBINED SPARK-PLUG AND VAPORIZER FOR INTERNAL-COMBUSTION ENGINES.

1,099,365.

Specification of Letters Patent.

Patented June 9, 1914.

Application filed January 21, 1914. Serial No. 813,467.

To all whom it may concern:

Be it known that I, JOHN C. HENDERSON, a citizen of the United States of America, residing at Washington, in the District of Columbia, have invented certain new and useful Improvements in a Combined Spark-Plug and Vaporizer for Internal-Combustion Engines, of which the following is a specification, reference being had to the accompanying drawings and to the numerals of reference marked thereon.

My invention relates to an improved spark plug and electrically heated fuel vaporizer for internal combustion engines.

15 In the operation of starting gas engines it is a well-known fact that the fuel, after having been heated in the carbureter or manifold, is cooled on striking the relatively cold cylinder walls, thus rendering it difficult to 20 ignite the charge. In order to obviate this difficulty I heat the fuel charge to a highly volatile state at the point of ignition during the period of starting the engine.

The object of my invention is to improve 25 the starting of an internal combustion engine by bringing the fuel admitted to the cylinder of said engine to a high point of vaporization; that is, the fuel that is to be utilized in the engine cylinder may be vaporized or supervaporized according to the state 30 it may be in when admitted to said cylinder.

A further object of my invention is to provide a unitary structure consisting of a 35 spark plug and an electrically heated vaporizer that can be placed without change in the standard spark plug opening of the cylinder of a gas engine, thus eliminating any machine work or special skill on the part of the user.

40 The present invention consists in a spark plug provided with an electrically heated vaporizing coil in close proximity to the sparking electrodes for the purpose of raising the temperature of the fuel in proximity 45 to said electrodes. The fuel in the vicinity of the spark plug will thus be in a highly volatile state at the point of ignition when the arc stream is passing between the electrodes for the purpose of exploding the 50 charge of gaseous fuel. As soon as the engine has fairly started, the current can be cut off from the electrically heated vaporizing coil. However, no harm will result 55 should the coil be permitted to remain permanently in circuit, but this is not con-

sidered necessary. In extremely cold weather it has, however, been found advisable to permit the vaporizer coil to remain in circuit with the engine running, until the engine parts have been heated sufficiently to 60 carry on the work that the vaporizer has started.

The novel features which I believe to be characteristic of my invention will be definitely indicated in the claims appended here-to; the features of construction and mode of operation will be understood by reference to the following description taken in connection with the accompanying drawing, which shows the preferred embodiment of my invention in longitudinal cross section, and in which:—

1 represents a standard spark plug-nipple; 2 denotes a nut for holding the porcelain plug 3 in the nipple 1. Between the plug 3 and the shoulder 4 of the nipple 1 is a packing washer 5 of heat resisting material such as asbestos, that acts as a cushion to prevent the fracturing of the plug when forced into place by nut 2.

The porcelain plug 3 is pierced its entire length for the reception of the electrode 6, that is provided at its uppermost end with a terminal 7. The nipple 1 at its lower end is provided with an electrode 8, thus forming with the electrode 6, the standard jump spark gap.

The heater or vaporizer is mounted upon the lower end of the porcelain body 3 and in close proximity to the jump spark electrodes 6 and 8, and consists of an electrically heated coil 9 of high resistance wire, embedded in the porcelain body 3 or enameled upon the surface thereof with porcelain enamel. The object of this is to prevent the products of combustion from the ignition of the motive fluid that may lodge or accumulate thereon from short circuiting or reducing the resistance of the heating element. One end of the coil is secured to the electrode 6, while the other end 11 is carried through an opening 12 in the body of the porcelain plug 3. This end of the heating coil is secured to the two part terminal clamp 13.

The heating circuit comprises the source 105 of supply (not shown), the switch 14, terminal 7, electrode 6, heating coil 9, terminal 13, back to the source of supply.

In accordance with the provisions of the patent statutes, I have described the prin- 110

ciple of operation of my invention, together with the article which I now consider to represent the best embodiment thereof; but I desire to have it understood that the article 5 shown is merely illustrative, and that the invention can be carried out by other equivalent means.

What I claim as my invention and desire to secure by Letters Patent is:—

- 10 1. A combined spark plug and fuel vaporizer, comprising the combination of a frame, an insulating plug, a pair of electrodes, and an electrically heated vaporizer mounted in proximity to the electrodes.
- 15 2. A combined spark plug and fuel vaporizer, comprising the combination of a frame, an insulating plug, a pair of electrodes, and an electrically heated vaporizer carried by the frame and in proximity to the electrodes.
- 20 3. A combined spark plug and fuel vaporizer, comprising the combination of a frame, an insulating plug, a pair of electrodes, and an electrically heated vaporizer

mounted on the insulating plug in proximity 25 to the electrodes.

4. A combined spark plug and fuel vaporizer, comprising the combination of a frame, an insulating plug, a pair of electrodes, and an electrically heated vaporizer 30 mounted on the end of the insulating plug in proximity to the electrodes, and covered with a vitreous enamel.

5. A combined spark plug and fuel vaporizer, comprising the combination of a 35 metallic frame, an electrode secured thereto, an insulating plug, an electrically heated vaporizer, and an electrode in said insulating plug for conveying current to the first mentioned electrode and one end of the vaporizer coil.

In witness whereof I have hereunto set my hand this 21 day of Jan. 1914.

JOHN C. HENDERSON.
